Filed July 22, 1968, Ser. No. 12,844

Term of patent 14 years

Int. Cl. D22—07

U.S. Cl. D22—29

FIGURE 1 is a perspective view of the ornamental design for a fish lure;

FIGURE 2 is a side elevational view thereof;

FIGURE 3 is a back elevational view;

FIGURE 4 is a top view thereof;

FIGURE 5 is a bottom view thereof.

The characteristic features reside in the substantially uniform and continuous pattern of chevron-shaped ribs extending across the longitudinally curved lure, all as shown.

I claim:

The ornamental design for a fish lure, substantially as shown and described.
